JAMES ALLEN KAMMERDINER, OF LOS ANGELES, CALIFORNIA, ASSIGNOR OF TEN ONE-HUNDREDTHS TO O. P. YOWELL, TEN ONE-HUNDREDTHS TO S. R. ROBINSON, TEN ONE-HUNDREDTHS TO Z. A. DYER, AND TEN ONE-HUNDREDTHS TO C. T. ALLEN

CASING CUTTER

Application filed December 21, 1925. Serial No. 76,664.

This invention relates to a device for severing tubular members. It is especially useful in cutting casings in oil well holes and like places. For various reasons, it is often necessary or advisable to cut casing within the hole and at a considerable depth. The present invention has for its primary object the provision of a tool which may be inserted in the hole about the work or member to be cut in the manner of an overshot fishing tool. That is, the tool encircles or embraces the work or casing to be cut and slides along on it while being lowered to the desired point. The tool is then caused to puncture and sever the member by moving the tool upwardly. Another object of this invention is to provide a tool of the character described which produces a severance by progressively perforating the work along the line of severance so as to finally produce a peripheral cut. The ultimate object of this invention is to produce a cutter which requires an operating force of relatively small magnitude and may be operated by pulling upwardly.

These objects together with other objects and corresponding accomplishments are obtained by means of the embodiment of my invention illustrated in the accompanying drawing, in which:

Fig. 1 is an axial section through a cutting tool showing it disposed about a casing and in position for operation; Fig. 2 is a section as seen on the line 2—2 of Fig. 1; Fig. 3 is an axial section on an enlarged scale showing a fragment of the tool and the casing with a knife in position about to perforate the casing; and Fig. 4 is a view similar to Fig. 3 showing a knife after it has performed its cutting function.

Referring more particularly to the drawings, A and B indicate joints of casing joined by a coupling C. This is the usual structure of the casing string. It will be assumed that the casing is to be cut below the coupling.

A tubular body or shell 5 has a bore extending therethrough and indicated by 6 so it may be passed over the casing and couplings. The bore is constricted at the top as indicated by 7. It is counterbored and internally threaded as indicated by 8 to receive the end of a pipe

9 forming the string for operating the tool. An enlargement 10 is provided at an intermediate portion of the bore to receive an abutment ring later described. The bore is still further enlarged as indicated by 11 for receiving knife carrier rings. The lower end of the bore is threaded as indicated by 12 to receive a shoe 13.

Slidably mounted within the portion 10 of the bore is a ring 14 having spring fingers 15 secured thereto and extending upwardly. These fingers are arranged to press inwardly against the string of casing and to engage the underside of adjacent coupling C which forms, in effect, a shoulder, if the ring is moved upwardly. Extending through registering openings in the body and ring is a shear pin 16. This pin yieldably retains ring 14 in longitudinal position and constitutes a frangible member, that is when sufficient force is exerted upon ring 14 tending to move it downwardly, the pin 16 will be sheared as shown in Fig. 3. The ring has a shoe as indicated by 17 at its lower end which is preferably made of soft metal.

Disposed within the portion 11 of the bore of the body is a plurality of knife carriers or cages 18 to 22. These comprise rings which are similar in construction and dimensions and are held in position by the shoe 13. The internal diameters of the rings correspond to the external diameter of the abutment ring 14 so that it may be slidably moved therewith. Referring to ring 18, it has a number of longitudinally extending slots or recesses 23 in which are disposed knife blades 24. The blades have sharp ends for engaging and perforating the casing. They are pivoted on pins 25 in the carrier so that they may be turned about their pivots moving inwardly. The pins or axes 25, extend peripherally about ring 18, as clearly shown in Fig. 2. Each knife is provided with a tooth or ledge 26 arranged to receive a binding wire 27 when the knives are in their upper or initial inoperative position, as shown in Fig. 1. The wire lies in a groove 28 in the peripheral surface of the carrier. The knives are freely mounted on their pivot pins and would drop downwardly, unless held in their upper po-

100

sition. The binding wire serves for this purpose and is a frangible retention member, it being easily sheared when pressure is exerted thereon. In the present structure there are five carrier rings shown, each having a set of knives spaced about its periphery, the carrier rings serving to space the knives longitudinally. In assembling the carriers or cages in the shell 5, the knives should be disposed peripherally in staggered relation. This may be insured by having dowel pins 29 engaging corresponding recesses in the ends of the carrier rings.

Assume that the tool has the knives arranged in their upper or initial inoperative position as shown in Fig. 1. If it is desired to sever a casing, the tool is lowered into the hole and over the casing by means of the pipe 9. When the tool has reached the position at which it is desired to cut the casing, it is elevated, the fingers 15 engaging below the coupling C. This prevents the ring 14 from moving upwardly with the tool, and, if sufficient force is exerted, pin 16 will be sheared. This permits the shell or body of the tool to be moved upwardly while the abutment ring 14 remains stationary. The set of knives on carrier ring 18 engage the lower end of the abutment ring, as shown in Fig. 3, and shear wire 27, and are turned inwardly against the casing so as to puncture the latter. Continued movement of the tool upwardly causes the knives to be withdrawn and to be disposed in the final inoperative position shown in Fig. 4. Next the set of knives in carrier ring 19 engage the abutment ring and the binding wire is sheared, the knives being turned inwardly and puncturing the casing at points intermediate the other perforations, producing another set of perforations. The knives in carrier ring 20 next act and then those in rings 21 and 22. The perforations produced by all of the knives acting sever the pipe completely and the latter may then be raised with the tool. It will be noted that the cutting is accomplished by perforating the pipe at intervals so that the magnitude of force required is comparatively small.

What I claim is:

1. A tool of the character described comprising a shell for slidably embracing the work to be severed, an abutment member disposed within said shell so as to be yieldably retained in longitudinal position therein, said abutment member having means to engage a shoulder on the work when moved in one direction, a plurality of spaced annular knife cages mounted in said shell, each of said cages having longitudinally extending recesses, knives pivotally mounted within the recesses of said cages on peripherally extending axes, the knives in each cage being staggered with respect to the knives in the other cages, said knives being arranged to be swung in a continuous movement from an initial inoperative

position inwardly to be disposed on either side of their axes so as to penetrate the work and then be withdrawn into an inoperative position again, said abutment member being arranged to be engaged by the knives in the cages in seriatim to swing the latter.

2. A tool of the character described comprising a shell for slidably embracing the work to be severed, an abutment member disposed within said shell so as to be yieldably retained in longitudinal position therein, said abutment member having means to engage a shoulder on the work when moved in one direction, a plurality of annular knife cages mounted in said shell, each of said cages having longitudinally extending recesses, knives pivotally mounted within the recesses of said cages on peripherally extending axes, the knives in each cage being staggered with respect to the knives in the other cages, said knives being arranged to be swung in a continuous movement from an initial inoperative position inwardly so as to penetrate the work and then be withdrawn into inoperative position again, and yieldable retention means to hold said knives in initial inoperative position, said abutment member being arranged to be engaged by said knives to swing the latter.

3. A tool of the character described comprising a shell for slidably embracing the work to be severed, an abutment ring slidably disposed within said shell, a frangible member securing said ring in longitudinal position in said shell, fingers on said ring adapted to engage under a shoulder on the work whereby force exerted on said ring tending to displace the latter may break said frangible member and release said ring, a knife cage mounted in said shell having longitudinally extending slots, knives pivotally mounted within the slots of said cage on peripherally extending axes, said knives being arranged to be swung in a continuous movement from an initial inoperative position inwardly so as to penetrate the work and then be withdrawn into inoperative position again, said abutment ring being arranged to be engaged by said knives to swing the latter, and a frangible retention member encircling said cage and holding said knives in initial inoperative position.

4. A tool of the character described comprising a shell for slidably embracing the work to be severed, an abutment ring slidably disposed within said shell, a frangible member securing said ring in longitudinal position in said shell, fingers on said ring adapted to engage under a shoulder on the work whereby force exerted on said ring tending to displace the latter may break said frangible member and release said ring, a plurality of annular knife cages mounted in said shell, each of said cages having longitudinally extending slots, knives pivotally

mounted within the slots of said cages on peripherally extending axes, the knives in each cage being staggered with respect to the knives in the other cages and arranged to be swung in a continuous movement from an initial inoperative position inwardly so as to penetrate the work and then be withdrawn into inoperative position again, said abutment ring being arranged to be engaged by 10 said knives to swing the latter.

5. A tool of the character described comprising a shell for slidably embracing the work to be severed, an abutment ring slidably disposed within said shell, a frangible member 15 securing said ring in longitudinal position in said shell, fingers on said ring adapted to engage under a shoulder on the work, whereby force exerted on said ring tending to displace the latter may break said frangible 20 member and release said ring, a plurality of annular knife cages mounted in said shell, each of said cages having longitudinally extending slots, knives pivotally mounted within slots of said cages on peripherally extending axes, the knives in each cage being staggered with respect to the knives in the other cages, said knives being arranged to be swung 25 in a continuous movement from an initial inoperative position inwardly so as to penetrate the work and then be withdrawn into inoperative position again, said abutment ring being arranged to be engaged by said knives in their initial inoperative position and to swing the latter, and a frangible 30 retention means for each cage encircling the latter and engaging the knives therein to hold the latter in their initial inoperative position.

6. A tool of the character described comprising a body for slidably embracing the 35 work to be severed, an abutment member disposed within said body so as to be yieldably retained in longitudinal position therein, said abutment member having means to engage a shoulder on the work to prevent movement 40 in one direction, sets of knives pivotally secured to said body on peripherally extending axes, said sets of knives being disposed at different levels, said knives being mounted to be swung inwardly in a continuous movement 45 so as to penetrate the work and be withdrawn to final inoperative position, said abutment member being arranged to be engaged by said sets of knives in seriatim and to swing the latter, and yieldable retention 50 means to hold said knives in initial inoperative position.

In witness that I claim the foregoing I have hereunto subscribed my name this 12th day of December, 1925.

60 JAMES ALLEN KAMMERDINER.
